SWINGING CHAIR

Robert Bigham Smith, Macon, Ga.

Application April 29, 1931, Serial No. 533,656

6 Claims. (Cl. 155--5)

The invention relates in general to a folding or tilttable chair or seat of general application wherever such articles are adapted for use. The invention particularly relates to a seat or chair 5 designed for use as the front tilttable seat of an automotive vehicle or in any similar situations where it is desirable to provide a form of folding seat which can be moved quickly into an out-of-the-way position leaving an unobstructed 10 clearance for entrance or egress from the vehicle or past the rear side of the tilted seat.

The primary object of the invention is to provide a simplified form of folding seat which will be secured in its normal position against accidental folding or turning; which will be positively secured in such position and locked securely in position.

Another object of the invention is to provide a form of securing latch which will be self operating to hold the seat in its normal position automatically as an incident of moving the seat into such position, and to provide a form of latch control for releasing the same which will be simple in construction and operation, which will be conveniently accessible along one of the exposed edges of the seat and which will be disposed so as to be unobtrusive and preferably concealed either by the chair itself or by the adjacent portion of the car structure.

Various other objects and advantages of the invention will be in part obvious from an inspection of the accompanying drawing and in part will be more fully set forth in the following particular description of one form of mechanism embodying the invention, and the invention also 35 consists in certain new and novel features of construction and combination of parts hereinafter set forth and claimed.

In the accompanying drawing:

40 Fig. 1 is a view in side elevation of a preferred embodiment of the invention shown in full lines in its normal, righted position and shown locked in such position, and in dotted lines shown in its tilted position released from its locked position;

45 Fig. 2 is an enlarged showing of the lower portion of the seat shown in Fig. 1 showing the position of the parts as the latch is about to engage its keeper; and

50 Fig. 3 is a view in end elevation of the latch and associated parts shown in the preceding figures and with parts broken away to show details of construction.

In the drawing and referring first to the showing in Fig. 1, there is disclosed a floor or other 55 suitable support 10 on which is positioned a chair

11 in this instance shown to include a seat 12 and a back 13, the back and seat being constructed rigid relative to each other. It is obvious, however, that insofar as the structure shown is concerned, the back 13 may be of the folding type 60 commonly designed to fold down on top of the seat.

The chair is supported at its front edge on a hinge mounting 14 about which the chair as a whole may be turned when elevated from its normal position as shown in full lines in Fig. 1 and swung forwardly as shown in dotted outlines and following conventional practices in this respect. There is also illustrated a coiled spring 15 which tends normally to either swing the chair about 65 the pivotal mounting when released from the latch hereinafter described or which will tend to assist in lifting and swinging the chair into its forward, inoperative position.

The seat 12 is provided adjacent its rear edge 70 with a foot 16 which engages the support 10.

For the purpose of holding the chair in its normal position and against the turning action of the spring 15, there is provided a latch 17 pivoted on fulcrum pin 18 mounted in bracket 19 75 secured to the frame 20 of the chair and positioned to one side of the seat 12. The latch has its lower end beveled as shown at 21 which beveled end is designed to project downwardly into recess or opening 22 formed in the support or floor board 10. The lower end of the latch is of the conventional shouldered construction with the shoulder 22 designed to engage under a keeper 23 secured to the upper side of the support 10. The latch is maintained in engagement with its keeper by a coiled spring 24, one end of which is secured to the latch and the other end secured to an anchor 25 fastened to the underside of the seat.

The upper end of the latch is formed into a handle 26 disposed below the level of the seat as shown in Fig. 1, and to one side thereof as shown in Fig. 3, and designed so as to be conveniently accessible either to the occupant of the seat so that the latch may be unlocked as the occupant leaves the seat, or in the case of the device being used on an automobile, the latch and particularly its handle is preferably so disposed as to be readily operated by a person standing outside of the car and reaching through the open door to the latch handle. In operation it will be understood that with the parts shown in the position illustrated in full lines in Fig. 1, it is simply necessary to swing the latch into position 90 against the action of the spring 24 to permit the 100 105 110

latch to escape its keeper after which the rear end of the seat, or the back, may be lifted or pushed forwardly assisted in those cases where the turning spring 15 is utilized. As the chair is 5 swung from the dotted line back into its normal position, the pointed end of the latch will slide down past the keeper as shown in Fig. 2, thus placing spring 24 under tension and when the parts are restored to the position shown in Figs. 1 10 and 3, spring 24 will react on the latch to return the same into the holding position shown in Fig. 1 with the shoulder 22 disposed beneath the keeper.

I claim:

1. In a device of the class described, the combination of a support, a chair having a seat and a back rigid therewith, means adjacent the front edge of the seat providing a hinge mounting for the chair, a coil spring at the mounting tending to raise the rear end of the chair and to swing it 20 forwardly about said hinge mounting, a latch pivoted to the chair adjacent its rear end, a keeper secured to the support and adapted to be engaged by the latch for securing the chair in its normal position, a spring acting on the latch and tending to maintain it in engagement with the keeper and said latch provided with manually actuated control means easily accessible to the person occupying the chair.

2. In a device of the class described, the combination of a support provided with a recess, a folding seat provided at its front edge with a pivotal mounting, and at its rear edge with a supporting foot projecting rigidly therefrom, a vertically extending latch pivoted to one side of the 35 seat and having a pointed end adapted to project into said recess and having its upper end formed into an actuating handle disposed adjacent to and offset to one side of the seat, a keeper for the latch secured to the upper side of the support at 40 the recess and a spring beneath the plane of the seat, acting on the latch and tending to hold the same in engagement with the keeper.

3. In a device of the class described, the combination of a chair, means providing a pivotal mounting for the same adjacent its front edge, a 45 spring encircling the pivotal mounting and acting on the chair and tending to raise and swing the same about said mounting forwardly from its normal position, a latch means spaced rearwardly from said mounting for securing the chair 50 in its normal position against the tendency of said

spring to turn the same forwardly and manually actuated control means carried by the chair for releasing said latch means.

4. In a device of the class described, the combination of a chair including a seat and a back fixed relative to the seat, means providing a pivotal mounting for the chair adjacent the forward edge of the seat, a spring at the forward edge of the chair tending to turn the same about said pivotal mounting, a latch means adjacent the rear edge of the seat for holding the chair in its normal position against the action of said spring and a manually actuated control carried by the seat adjacent the back for releasing the latch means and thus permit the spring to elevate the 90 chair.

5. In a device of the class described, the combination of a chair, means providing a pivotal mounting for the same for causing the chair to turn about an axis of turn extending laterally across and beneath its front edge, and said chair movable about said axis of turn at the mounting when moved from its normal seated position into an elevated position, a spring at the pivotal mounting tending to urge the chair into its elevated position, a latch pivoted to the chair adjacent its rear edge for securing the chair in its normal seated position, a spring acting on the latch and tending to maintain it in its operative position, and said latch provided with an upwardly extending actuating handle movable in the act of releasing the latch in the same direction as the chair moves when turning into its elevated position about its pivotal mounting.

6. In a device of the class described, the combination of a chair, means providing a pivotal mounting for the same adjacent its front edge, said chair movable about an axis of turn at the mounting when moved from its normal seated position into an elevated position, a latch pivoted 110 to the chair adjacent its rear edge for securing the chair in its normal seated position, said latch provided with an upwardly extending actuating handle movable forwardly in the act of releasing the latch and in the same direction as the chair moves when turning into its elevated position about its pivotal mounting whereby the chair may be assisted in moving into its elevated position by a continuation of the pull on the handle following the releasing of the latch.

ROBERT BIGHAM SMITH.
